UNITED STATES PATENT OFFICE

156,065

DESIGN FOR A FLASHLIGHT

Robert J. Avery, Clearwater, Manitoba, Canada

Application February 26, 1948, Serial No. 144,737

Term of patent 7 years

(Cl. D48—24)

To all whom it may concern:

Be it known that I, Robert J. Avery, a citizen of the Dominion of Canada, residing at Clearwater, in the District of Lisgar, in the Province of Manitoba, Dominion of Canada, have invented a new, original, and ornamental Design for a Flashlight, of which the following is a specification, reference being had to the accompanying drawing, forming a part thereof.

Fig. 1 is a perspective view of a flashlight, showing my new design, and

Fig. 2 is a perspective view of the side opposite to that shown in Fig. 1.

I claim:

The ornamental design for a flashlight, as shown.

ROBERT J. AVERY.
